3 Claims. (Cl. 200—148)

This invention relates to circuit interrupters in general and, more particularly, to improved arc-extinguishing structures therefor.

A general object of the present invention is to provide an improved circuit-interrupting structure highly effective to extinguish currents over a wide current range and particularly effective in the higher current range.

In United States patent application filed January 23, 1959, Serial No. 788,668, now United States Patent 3,057-983, issued October 9, 1962 to Russell N. Yeckley, Joseph Sucha and Benjamin P. Baker, and assigned to the assignee of the instant application, there is described and claimed an interrupting unit of the gas-blast type in which a suitable arc-extinguishing gas is exhausted axially along an orifice structure in proximity to the established arc. This interrupter is highly effective throughout a wide current range. However, during very high-current interruptions, there is a tendency for a high-current limit to be reached because the orifice opening is "clogged" by the high-current arc, thereby preventing the rapid flow of gas, such as sulfur hexafluoride (SF_6) gas, necessary for quick interruption. The arc, in such circumstances, may persist for two or more cycles and be difficult to interrupt. Accordingly, it is a purpose of the present invention to provide an improved type of interrupter construction in which a cross-blast flow of gas will be obtained particularly for effective high current interruption.

Still a further object of the present invention is to provide an improved orifice-type interrupting unit in which a resistance is inserted serially into the connected circuit during interruption to lower the rate of rise of the recovery voltage, and to assist in rapid arc interruption.

Yet a further object of the present invention is to provide an improved orifice construction particularly suitable for withstanding high voltage tests and to eliminate the aforesaid clogging action by utilizing a metallic orifice to shield the stationary contact during such voltage tests, and, in addition, to eliminate the presence of an arc portion within the orifice itself.

Further objects and advantages will readily become apparent upon reading the following specification, taken in conjunction with the drawings, in which:

FIGURE 1 is a perspective view of a three-pole high-power circuit interrupter suitable for controlling the three phases of a transmission system, and illustrating an embodiment of the present invention;

FIG. 2 is a longitudinal vertical sectional view taken through one of the grounded tank structures of FIG. 1, illustrating the arc-extinguishing assemblage in side elevation, and showing the disposition of the contact structure in the closed-circuit position thereof;

FIG. 3 is an enlarged vertical sectional view taken longitudinally through one of the improved arc-extinguishing units of the multi-break arc-extinguishing assemblage of FIG. 2, the contact structure being illustrated in the closed-circuit position;

FIG. 4 is a fragmentary sectional view, somewhat similar to that of FIG. 3, but showing the location of the drawn arc during a portion of the opening operation;

FIG. 5 is an enlarged sectional view taken substantially along the line V—V of FIG. 3;

FIG. 6 is a fragmentary view of a modified type of

2

circuit-interrupting unit, the contact structure being illustrated in the partially open-circuit position;

FIG. 6A illustrates a slightly modified form of the circuit-interrupting unit of FIG. 6, again the contact structure being illustrated in the partially open-circuit position;

FIG. 7 illustrates, in vertical cross section, still a further modified type of interrupting unit;

FIG. 8 illustrates a fragmentary plan view of the movable contact assemblage taken substantially along the line VIII—VIII of FIG. 3, with certain parts omitted for clarity; and,

FIGS. 9 and 10 show a modified type interrupting unit in two consecutive intermediate positions of the opening operation.

Referring to the drawings, and more particularly to FIG. 1 thereof, the reference numeral 1 generally designates a three-pole high-voltage, high-power circuit interrupter suitable for controlling the three phases of a transmission system. Pole-unit A controls the lines L_1 and L_2 ; pole-unit B controls the transmission line L_3 , L_4 ; and pole-unit C controls the current phase passing through line L_5 , L_6 . As shown, the circuit interrupter 1 comprises a plurality of generally horizontally-extending grounded metallic tank structures 2 having end covers 3 associated therewith. The end covers 3 may be rotated about vertical hinge pins, not shown, to permit inspection into the interior of the tank structures 2 and withdrawal of the arc-extinguishing assemblage 4 (FIG. 2) laterally out of the tank structure 2 when such a maintenance operation is desired.

Disposed at opposite ends of the several tank structures 2, and extending upwardly therefrom, are supporting cylinders 5 having flanged apertured upper support plates 6, the latter serving to rigidly support into position entrance-type terminal-bushing structures 7. As well known by those skilled in the art, the terminal bushings 7 serve the function of transmitting the current to be interrupted into the interior of the tank structures 2. In addition, as more clearly shown in FIG. 2, the lower ends 8 of the terminal bushings 7 serve to support the arc-extinguishing assemblage 4, in bridging relation therewith, in a relatively fixed position.

Disposed below each of the horizontally-extending elongated tank structures 2 are auxiliary high-pressure storage tanks 11, which cooperate with the high-pressure reservoir chamber 11A (FIG. 2) which is disposed at the right-hand end of each of the several arc-extinguishing assemblages 4, as more clearly shown in FIG. 2. A mechanism housing 12 is provided which encloses the gas-control equipment, and a suitable compressor, not shown, which is employed to extract relatively low-pressure gas from the interior 13 of the several tank structures 2 and to recompress it, forcing the recompressed gas back, by a suitable pipeline, not shown, to the auxiliary high-pressure reservoirs 11 and 11A. A high-pressure connecting tube 14 (FIG. 2) interconnects each high-pressure reservoir 11 with the high-pressure reservoir 11A, which constitutes the right-hand extremity of each arc-extinguishing assemblage 4, as more clearly shown in FIG. 2.

Disposed interiorly within the mechanism housing 12 is a suitable operating mechanism, for example one of the pneumatic type, which functions, by a suitable linkage, to effect reciprocal motion of an operating shaft, not shown, disposed interiorly within an operating tube 15 (FIG. 1) which interconnects the several pole-units A, B and C.

Encircling each of the terminal bushings 7 are current transformers 16, which serve to measure the current flow through the circuit interrupter 1 and also serve thereby to operate protective relaying equipment. Conduits 17 serve to carry the secondary leads of the current transformers

16 interiorly within the mechanism housing 12, in which a trip mechanism may be positioned.

With reference to FIG. 2, it will be observed that the arc-extinguishing assemblage 4 includes a rigid framework maintained in fixed position by insulating support bars 18, which are bolted, as at 19, 20 to support castings 21, 22. The support castings 21, 22 are fixedly secured to the lower ends 8 to the terminal bushings 7. As shown, the high-pressure reservoir chamber 11A is bolted to the right-hand support bracket 22 of the arc-extinguishing assemblage 4.

Associated with the high-pressure reservoir chamber 11A is a blast valve 23 (FIG. 3) biased to the closed position by a compression spring 24, and opened by a pilot-valve assembly 27 (FIG. 2) as set out more in detail in the aforesaid patent application. The blast valve 23 is operated by a pneumatic valve piston, not shown, which, in turn, is operated by the pilot-valve assembly 27 (FIG. 2), operated by a main operating lever 28, pivotally mounted at 29. The main operating lever 28 has a pair of thrust-links 31 (only one being shown in FIG. 2) pivotally secured thereto, as at 32. The left-hand ends of the two thrust-links 31, as viewed in FIG. 2, are pivotally connected to the right-hand ends of the two spaced movable operating rods 33 (FIG. 2), which move in a reciprocal manner, back and forth, during the opening and closing operations, as viewed in FIGS. 1 and 2.

Interconnecting the left-hand ends of the two spaced insulating operating rods 33, as viewed in FIG. 2, is a bridging spring-plate 34, which is biased toward the left by a compression spring 35. At the end of the opening operation, the spring-plate 34 strikes the bumper stop 36 and is arrested thereby bringing the entire movable contact assemblage to a cushioned stop.

Spaced axially along the insulating operating rods 33, and bridging the two operating rods 33, are a plurality of movable contact cross-arms 37 (FIG. 8). The cross-arms 37 are pinned to the two spaced insulating operating rods 33, and form a generally movable ladder-like contact assemblage 39. Adjacent the center of each cross-arm 37 (FIG. 8) is pinned, by a guide pin 38, an extension 41 of a movable contact 42. As shown more clearly in FIG. 3, the movable contact 42 makes contacting engagement with a relatively stationary contact 43, the latter having a plurality of resilient end fingers 44. Preferably arc resisting tip portions 44A are associated with the extremities of the resilient finger contacts 44 to assume the arcing during the opening operation. The end of the movable contact 42 is provided with a vented recessed portion 46, within which projects the left-hand end of the relatively stationary contact 43, as shown in FIG. 3 of the drawings. A plurality of lateral vents 46A communicate with the recess portion 46 of movable contact 42, as shown.

Surrounding the relatively stationary and movable contacts 42, 43 in the closed-circuit position of the device, as illustrated in FIG. 3, is a metallic orifice structure, generally designated by the reference numeral 48. As shown, the orifice structure 48 includes a removable orifice plate 49, which preferably has an arc-resisting orifice liner 50. As shown in FIG. 3, in the closed-circuit position of the interrupter 1, the movable contact 42 extends through the orifice opening 51 and makes contacting engagement with the relatively stationary contact 43. Due to the resiliency of the relatively stationary contact fingers 44, a good current transfer is obtained therebetween.

An insulating gas-directing tube 47 is associated with each unit 10, being disposed forwardly of the orifice opening 51, and defining an outer interrupting chamber generally designated by the reference number 52.

During the opening operation, the movable operating rods 33 are moved toward the left, as viewed in FIG. 3, causing thereby a separation between the several movable contacts 42 and the relatively stationary contacts 43 of the several interrupting units 10 to establish a plurality of serially related arcs 53. Since the orifice structure 48 of

each interrupting unit 10 is composed of a metallic material, the arc 53 quickly transfers from the relatively stationary contact 43 to the orifice liner 50 in a manner more clearly shown in FIG. 4 of the drawings. In addition, FIG. 4 shows a modified type movable contact 42A having an unvented recess 46, as shown.

As more fully brought out in the aforesaid patent application, the blast valve 23 is opened at, or slightly before the separation of the movable contacts 42, 43 to cause a blast of high pressure gas to pass from the high-pressure tank 11A through the blast tube structure, or conducting blast entrance chamber 54 and into the orifice region 55. There occurs a rapid rise of pressure within the orifice region 55 to effect an ejection of high-pressure gas out through the constricted orifice opening 51 to direct a cross blast of gas across the arc 53, as indicated by the arrows 56 in FIG. 4 of the drawings. It will be noted that even though a very high-current arc is drawn, nevertheless due to the fact that the orifice structure 48 is composed of metallic material, there will be no arc portion present within the interior region 55 of the orifice structure 48. As shown in FIG. 4, the arc 53 will be positioned exteriorly of the orifice structure 48, and will receive the direct cross-blast effect of the high-pressure gas therethrough, which will quickly effect its extinction.

FIG. 6 illustrates a modified type of interrupting unit 58 in which the body of the orifice structure 59 is composed of a suitable resistance material, such as carbon. The magnitude of the resistance in the modified type of interrupting unit 58 of FIG. 6 may vary from substantially 12 ohms to 200 ohms depending upon the current and voltage rating of the circuit-interrupting device.

It will be apparent that upon separation of the movable contact 60 from the relatively stationary contact 61 a main current arc, generally designated by the reference numeral 62, will be established. Because of the presence of the adjacent resistance material comprising the orifice structure, and because of the longitudinally flowing gas blast at high pressure through the constricted orifice opening 51, the main current arc will be extinguished, and there will result a residual current arc 63 extending between the tip portion 64 of the movable contact 60 and the orifice liner 50. The insertion of the resistance material serially into the circuit will lower the rate of rise of the recovery voltage and will also improve the power factor of the resultant circuit to be interrupted. Again the gas blast will pass in the direction indicated by the arrows 66 of FIG. 6, and the arc will quickly be extinguished.

The interrupter shown in FIG. 6 causes interruption in a manner similar to that of Patent 3,057,983, in that the arc is forced to remain in the center of the orifice 51 by the resistor 59. The axial flow of gas forces interruption. If the arc 62 attempts to transfer to the metal orifice 59 immediately after the contacts part, the subsequent voltage rise, caused by the insertion of the resistor, will cause an immediate breakdown of the gap between the contact tip 64 and the fingers 61. The process forces the power arc 62 to stay in the center of the orifice 51 until a sufficient gap is available to withstand the recovery voltage. The resistor current 63 will then be interrupted in the manner previously described.

Instead of forming the body of the orifice structure of a suitable resistance material, such as carbon, the same effect may be produced, namely of insertion of the resistance serially into the circuit, by using the construction set forth in FIG. 6A of the drawings. With reference to FIG. 6A, it will be noted that a separate resistance tube 70 is employed composed of insulating material, surrounding which may be helically wound a resistance wire 71. In this modified construction, the orifice body may be of a suitable insulating material 73. The manner of interruption will be the same as set forth in connection with FIG. 6 of the drawing, namely the interruption of

the main current arc by the insertion into series circuit of the resistance material. Again the resistance value may vary from say substantially 12 ohms to 200 ohms depending on the current and voltage requirements of the device.

FIG. 7 shows a further modified form of the invention in which a modified type of interrupting unit 75 utilizes a tubular movable contact 76 having slotted portions 77 to form a plurality of circumferentially disposed resilient contact fingers 78. The contact fingers 78 resiliently engage the interior surface 79 of the orifice liner 80 in a manner more clearly shown in FIG. 7 of the drawings. During the opening operation, the movable contact 76 is drawn toward the left by the left-hand opening movement of the movable contact assemblage 39 in the manner previously described. The orifice structure, being of metallic material, will effect drawing the arc externally of the orifice, in the manner illustrated in FIG. 4 of the drawings. It will be noted in connection with this modification of the invention, that the relatively stationary contact structure 43, 61 is omitted and the orifice liner 80 itself constitutes the relatively stationary contact. Preferably, the outer side of the orifice liner 80 is beveled, as at 80A, to assist in guiding the closing movement of the movable contact 76.

FIG. 9 is a modification of the interrupter construction of FIG. 6 wherein the stationary contact 61 has been moved rearwardly of the orifice construction 50. In the modified interrupter unit 85 of FIG. 9, a vented movable contact 86 is utilized. The drawn main or power arc 87 is maintained between the moving contact 86 and the stationary contact 61 by the action of the resistor 88. If the main arc 87 attempts to transfer to the metal orifice 50 shortly after the contacts 86, 61 part, the subsequent voltage, caused by the insertion of the resistor 88, will cause an immediate breakdown of the gap between the contact 61 and the contact 86. The arc is interrupted by the flow of gas through the center of the hollow contact 86. The location of the orifice 50 forces the gas to flow through the center of the contact 86. The power arc 87 is generally interrupted before the contact 86 is withdrawn from the orifice 50. Subsequently, the resistor arc 89, as shown in FIG. 10 is interrupted by the gas cross-blast after the contact 86 is withdrawn from the orifice 50.

From the foregoing description of several embodiments of the invention, it will be apparent that there is provided an improved orifice construction for an orifice-type interrupting unit in which by the use of metallic orifices the presence of an arc length within the orifice region is prevented. As a result, the arc is drawn externally of the orifice region, and consequently there is avoided clogging of the orifice opening by ionized gas resulting from a high-amperage arc drawn within the orifice region. The present interrupting unit is particularly suitable for circuit interrupters interrupting very high-amperage currents, where otherwise there would be a tendency for clogging to occur within the orifice interior. By an application of the present invention, such clogging is prevented, and a highly effective cross-blast of the arc-extinguishing gas is provided to quickly effect arc extinction and consequent circuit interruption. By incorporating a resistor, a simple and effective method of insertion is accomplished by using the metal orifice as described.

Although there has been illustrated and described specific structures, it is to be clearly understood that the same were merely for the purpose of illustration, and that changes and modifications may readily be made therein by those skilled in the art, without departing from the spirit and scope of the invention.

We claim as our invention:

1. A gas-blast circuit interrupter including means defining a source of high-pressure gas, means defining a blast entrance chamber composed of conducting material, blast-valve means interposed between said high-pressure source and said conducting blast entrance chamber, a relatively stationary contact supported by a rear conducting wall portion of said conducting blast entrance chamber, a forwardly-projecting generally cylindrically-shaped gas-directing resistance orifice member wholly composed of resistance material and having a restricted orifice opening disposed adjacent its forward end, a conducting arcing ring lining the restricted orifice opening to which an arc may attach, a movable tubular vented contact movable with slight clearance through said restricted orifice opening and into the interior of the orifice member to make separable opening and closing engagement with the relatively stationary contact therein, the opening of the blast-valve means causing a blast of high-pressure gas to flow into said conducting blast entrance chamber to thereafter be guided by said resistance orifice member and into the interior of the vented movable tubular contact, said flow of gas causing the insertion into series circuit of the resistance of said orifice member and extinction of the main power arc extending between the separable contacts, a residual-current arc being established between said conducting arcing ring and the movable tubular vented contact, and the continuous exhausting of high-pressure gas out of said resistance orifice member causing a cross-blast extinguishing action to be exerted upon the residual-current arc extending between the arcing ring at the orifice restriction and the movable tubular vented contact.

2. The combination according to claim 1, wherein the separation distance between the stationary contact and the orifice restriction is such as to cause extinction of the main power arc prior to withdrawal of the movable tubular vented contact out of the orifice restriction.

3. The combination according to claim 1, wherein the resistance of the orifice member ranges from substantially 12 ohms to 200 ohms.
